US0D1062747S

(12) **United States Design Patent** (10) **Patent No.:** **US D1,062,747 S**
(45) **Date of Patent:** **** Feb. 18, 2025**

(54) **LAPTOP STAND**

(71) Applicant: **Shenzhen Jianyi Technology Co., Ltd.**,
Guangdong (CN)

(72) Inventor: **Gang Guo**, Guangdong (CN)

(73) Assignee: **SHENZHEN JIANYI
TECHNOLOGY CO., LTD.**,
Guangdong (CN)

(**) Term: **15 Years**

(21) Appl. No.: **29/876,547**

(22) Filed: **May 24, 2023**

(51) LOC (15) Cl. **14-99**

(52) U.S. Cl.

USPC **D14/447**

(57) **CLAIM**

The ornamental design for a laptop stand, as shown and described.

DESCRIPTION

FIG. 1 is a front, top perspective view of a laptop stand, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the laptop stand that form no part of the claimed design.

1 Claim, 8 Drawing Sheets
